UNITED STATES PATENT OFFICE

117,699

DESIGN FOR A STORAGE BATTERY CASE

Oliver O. Rieser, Oak Park, Ill., assignor to The Richardson Company, Lockland, Ohio, a corporation of Ohio

Application March 13, 1939, Serial No. 83,550

Term of patent 7 years

To all whom it may concern:

Be it known that I, Oliver O. Rieser, a citizen of the United States and a resident of Oak Park, in the county of Cook and State of Illinois, have invented a new, original, and ornamental Design for a Storage Battery Case, of which the following is a specification, reference being had to the accompanying drawing, forming a part thereof.

In the drawing:

The single figure in the drawing is a perspective view of a battery box showing my new design.

The other side and end portions of applicant's battery box design are the same as the end portions shown in the drawing and the other side of the battery box does not carry the name plate shown in the drawing.

I claim:

The ornamental design for a storage battery case, substantially as shown and described.

OLIVER O. RIESER.
